(57) **CLAIM**

The ornamental design for a sleeper roof fairing, as shown and described.

DESCRIPTION

FIG. 1 is a perspective view of a sleeper roof fairing according to our new design;

FIG. 2 is a top view of the sleeper roof fairing of FIG. 1; FIG. 3 is a side view of the sleeper roof fairing taken from the right side of FIG. 1, the side view taken from the side opposite of FIG. 4 being mirror symmetrical thereto; and,

FIG. 4 is a front view of the sleeper roof fairing of FIG. 1. The rear and bottom of the sleeper roof fairing is unornamented.

The broken lines immediately adjacent the shaded areas as depicted in the FIGURES, represent the bounds of the claimed design while all other broken lines are directed to environment and are for illustrative purposes only; the broken lines form no part of the claimed design.
